APPARATUS FOR CLEANING GASES

Robert R. Harmon, Charlottesville, Va., assignor
to Peabody Engineering Corporation, New York,
N. Y., a corporation of New York

Application September 12, 1939, Serial No. 294,422

7 Claims. (Cl. 183—24)

This invention relates to apparatus for cleaning or purifying industrial gases or air and more particularly to a novel and improved apparatus of the type disclosed in my application 273,230, 5 which, in general, first removes the bulk of the coarse particles, then the fine particles of dust, fume or the like, and finally the tiny droplets of liquid which may be entrained by the gases.

An object of the present invention is to provide an apparatus of the above type which is readily adjustable for the treatment of different quantities of gas.

Another object is to provide an apparatus of the above type having adjusting means for maintaining predetermined gas velocities regardless of the volume of gas being treated.

Another object is to provide an apparatus of the above type which is readily adjustable to provide a wide range of capacities.

Another object is to provide, in an apparatus of the above type, novel and improved means for removing the droplets of entrained liquid which may be carried along with the gas.

Another object is to provide a dependable, efficient and commercially practicable apparatus for cleaning or purifying industrial gases or air.

Various other objects and advantages will be apparent as the nature of the invention is more fully disclosed.

Although the novel features which are believed to be characteristic of this invention are particularly pointed out in the claims appended hereto, the invention itself will be better understood by referring to the following description, 30 taken in connection with the accompanying drawings, in which certain specific embodiments thereof have been set forth for purposes of illustration.

In the drawings:

40 Fig. 1 is a vertical sectional view of a gas cleaning apparatus embodying the present invention;

Fig. 2 is a horizontal section taken on the line 2—2 of Fig. 1 with parts broken away to show the construction thereof;

45 Fig. 3 is an enlarged partial vertical section taken on the line 3—3 of Fig. 2;

Fig. 4 is a horizontal section taken along the line 4—4 of Fig. 1;

Fig. 5 is a partial vertical section of a cleaning 50 apparatus illustrating a different embodiment of the invention;

Fig. 6 is a horizontal section taken on the line 6—6 of Fig. 5; and

Fig. 7 is an enlarged vertical section illustrating 55 a further embodiment of the invention.

Referring to the drawings more in detail, the invention is shown in Figs. 1 to 4 as applied to a cleaning apparatus of the tower type, comprising a vertical or cylindrical shell or casing 10, having a conical bottom 11 terminating in a central drain 12 through which the waste liquid and entrained solid particles are withdrawn, and having a conical top 14 terminating in a central discharge duct 15 for the scrubbed gases. A gas inlet duct 16 is located in the bottom portion of 10 the casing 10. The inlet duct 16 is shown as inclined downwardly and entering the shell 10 beneath a baffle 17 for the purpose of preventing the gases from passing directly to the cleaning zone, to be described. It is to be understood, 15 however, that the inlet duct 16 may extend horizontally and may be located tangentially as shown in my copending application above referred to, if desired. The particular angle and location of this duct may depend, in general, 20 upon the size of the tower and the quantity of gases to be treated therein.

The lower portion of the shell 10, containing the gases above mentioned, may be considered to constitute a primary cleaning zone 20 in which 25 the bulk of the larger particles are removed from the gases and fall to the bottom 11 from which they may be removed through the drain 12.

The tower is also provided with a secondary cleaning zone 21 located above the primary cleaning zone 20 and comprising a circular plate 22 having an annular gas treating section 23 provided with a plurality of openings or orifices 24 (Figs. 2 and 3), each of which is of general venturi shape so as to impart a high velocity to the 30 gases passing therethrough. A baffle grid 25, comprising a plurality of strips 26 having outwardly extending baffles 27 formed thereon and supported by suitable means (not shown) is disposed above the plate 22 in a position such that 40 one of the baffles 27 is located in alignment with each of the orifices 24. The construction of the baffle grid and plate is more fully disclosed in my application above referred to and in my Patent No. 2,007,759, and only so much thereof is 45 set forth herein as is necessary to an understanding of the present invention.

For maintaining a blanket of cleaning liquid such as water on the plate 22, a rotating spray manifold 30 is provided. This manifold 50 comprises a plurality of radial arms 31 carrying nozzles 32 and rotated by suitable means such as a motor 33 driving the manifold through suitable means, disclosed as bevel gears 34. A supply pipe 35 may be provided to supply liquid to the mani- 55

fold 30. The rotating spray assembly may be mounted upon a pair of brackets 38 (Fig. 4) which are secured to the shell 10 by suitable means. It is to be understood, of course, that the 5 particular type of spray may be varied, as desired, and that the spray may be driven by other suitable means, such for example as by the reaction of the liquid discharged from the nozzles.

The plate 22 may be provided with an overflow 10 discharge pipe 40 terminating in a cup 41, or the like, to provide a liquid seal. In order to provide for adjustment of the effective area of the gas treating section 23 of the plate 22, the orifices 24 and the baffle grids 25 are shown as arranged in a plurality of segmental sections (Fig. 2). Cooperating with each of these sections is a louver 42 which is shown as attached to a rod 43 pivoted in ears 44 formed on the plate 22, and extending 15 outwardly through the shell 10, the end of the rod 43 being provided with an operating handle 45. Each louver 42 is shown in Fig. 3 as disposed above the baffle grid 25 and provided with a lip 46 which engages the plate 22 for supporting the louver and rendering ineffective the area 20 of the plate 22 beneath said louver. In this embodiment the baffle grid 25 is arranged in spaced segmental sections so as to provide clearance for the lips 46 of the various louvers 42 therebetween. 25

It is to be understood, however, that the baffle grid may be continuous around the entire plate 22 if desired, in which event the lips 46 may be omitted or may be modified to rest on the baffle grid. The bearings for the rods 43 are preferably adapted to exert sufficient friction so as to maintain the louver in elevated position as shown, for example, at the right of Fig. 3. If desired, however, suitable locking or latching means (not shown) may be provided for securing the 30 louvers in open position.

Disposed above the secondary cleaning zone 21 is a plate 50 (Fig. 1) carrying a plurality of drying units 51 disposed about the periphery thereof and registering in general with the various sections 23 of the plate 22. Each of the units 51 is shown as comprising a set of radially extending curved vanes 52 mounted between a fixed hub member 53 and a peripheral flange 54. Surrounding the flange 54 and spaced therefrom is a wall 55 having a conical top section 56 extending inwardly above the vanes 52 and joined at 57 to the lower edge of the flange 54 to form a liquid receiver channel 58 therebetween. The channel 58 communicates with an overflow pipe 59 terminating in a cup, or the like, 60 forming a liquid seal. In the embodiment shown, each unit 51 cooperates with a plurality of the segmental sections of the plate 22. It is to be understood, of course, that a separate unit 51 may be located over each section, if desired.

The peripheral edges of the plates 22 and 50 may be secured to the shell 10. The central portions of the plate 50 may be supported by struts 65 66' hung from the base of the discharge duct 15 or from the supporting framework thereof (not shown). These struts 66' may engage ears 61 formed on a ring 62 which is secured to the plate 50. Similar struts 63 may extend downwardly 70 and engage a ring 64 secured to the plate 22 for supporting the central portion thereof. The struts 66 and 63 are particularly useful in large towers in which the plates 22 and 50 may be of substantial size and would tend to sag unless some 75 central supporting means were employed.

Operation

In the operation of this device, the gas or air, heavily laden with dust, fume or other matter, enters through the inlet duct 16 where a large portion of the dust, fume or the like is removed from the gas stream and falls to the bottom of the shell. The gas then travels upward and is subjected to the action of the sprays from the slowly rotating nozzles 32. This spray feeds the liquid upwardly with the gas flow onto the under side of the annular section 23 of the plate 22.

The rotating sprays completely wash the bottom of the section 23 of the plate 22 and create a fine mist which passes through the orifices 24 along with the gas stream and suspended particles. The gas, suspended particles and mist strike the baffles 27 above the orifices 24 and the suspended particles are trapped by the mist and water which collects on top of the plate 22 to a predetermined depth depending upon the height of the overflow pipe 40.

A liquid blanket is maintained on the plate 22 due to the pressure and velocity of the gas passing through the orifices. Excess liquid collecting on the plate flows downwardly through the liquid seal formed by the cup 41. Gas which has thus been cleaned by causing the particles to impinge upon the baffle grid 25 and to be entrapped in the liquid on the plate 22 then passes upwardly 30 through the various drying units 51.

The vanes 52 of the units 51 impart a violent rotational movement to the gas. The entrained liquid particles are thus caused to coalesce on the under side of the vanes due to the wiping action 35 of the gases and are thrown off by the vanes 52 and against the wall 55 and the conical top portion 56 as large drops, thus drying the gas and relieving it of all entrained material. The liquid collecting in the channel 58 flows downwardly 40 through the pipe 59 onto the plate 22.

In the above described operation it is assumed that the various louvers 42 are in raised position as shown at the right in Fig. 3, thereby uncovering all of the baffle grids and orifices and permitting the entire area of the section 23 of the plate 22 to be active. It may, however, be desirable to close off a portion of the active area of the plate 22 as, for example, to increase the velocity of gas flow through the remaining portion or to maintain a constant or predetermined velocity when a reduced volume of gas is being passed through the tower. For this purpose a selected number of the louvers 42 may be closed as indicated at the left in Fig. 3, thereby shutting off the corresponding area of the baffle grid and plate 22 and reducing the number of orifices through which the gas may pass. The gas velocity may in this way be regulated as desired to adapt the tower to different types or quantities of gases and to pass the 50 gases through the secondary cleaning zone under 55 the most efficient conditions.

The relationship of the wall 55 to the vanes 52 is such that the rotating gases are caused to impinge against said wall so as to centrifugally remove the suspended droplets of liquid before the gases are passed to the top portion of the tower. The vanes 52 are preferably so spaced and curved that gases are progressively increased in velocity as they pass upwardly therethrough and are caused to rotate at the desired speed for obtaining the above results. By removing the entrapped liquid into the channel 58 the liquid is prevented from contacting with or being entrained in the rising gases.

It is to be understood that the particular 75

mounting for the louvers 42 and the particular type and operating mechanism therefor may be varied as desired. The louvers may, for example, be operated in groups or in unison by the use of suitable linkage means interconnecting the various rods 43. In certain instances it may be desirable to control the flow of gases by varying the angular position of the louvers 42, thereby changing the effective area available for gas flow. Other suitable adjusting means will be readily apparent.

Figures 5 and 6

In the embodiment of the invention shown in Figs. 5 and 6 the various parts of the tower corresponding to the parts described above, have been given similar reference numerals and the description thereof will not be repeated. It is noted that in Figs. 5 and 6 the louvers of Figs. 1 to 4 have been replaced by dampers 70. These dampers 70 are shown as mounted in separate segmental chambers 71 which are disposed above certain segmental sections or groups of sections 23 of the plate 22 and communicate with the individual units 51. In this embodiment the chambers 71 are closed by radial baffles 73 and by central closures 74. The central closures 74 are shown as forming a separate wall registering with the inner edge 15 of the dampers 70. The closures may, however, be of other shapes, such as circular, if desired.

Each damper 70 is shown as mounted on a rod 16 extending outwardly through the shell 10 and provided with an operating handle 77. In this embodiment the closure of any individual chamber 71 by means of the associated damper 70 prevents passage of gases through the corresponding central section of the plate 22 and into the unit 51 which is associated therewith. The gas is thus caused to flow through the remaining open chambers 71. In this way the gas velocity through the cleaning and drying zones may be regulated and a positive control of the entire operation may be obtained.

45

Figure 7

In the embodiment of Fig. 7 a plate 22 and baffle grid are shown similar to those above described and forming a part of the cleaning and scrubbing apparatus of the type above set forth. In this embodiment, however, the louvers 42 in Figs. 1 to 4 and the dampers 70 of Figs. 5 and 6 have been omitted and adjustment is obtained by means of a series of sliding plates 80, each of which is adapted to slide beneath the plate 22 and to close off a selected number of orifices 24. The plates 80 may each be provided with a lip 81 for engaging the under side of the plate 22 and may slide on suitable supporting guides 82. Each plate may be provided with a link 83 extending outwardly through the shell 10 and provided with a handle 84 by which the plate may be adjusted as desired. It is to be understood that a plurality of individual plates 80 may be provided for each of the segmental sections of the plate 22 and that the plates 80 may be variably adjusted to effect desired changes in the number of exposed orifices 24 which are available for use.

70 It will be noted that by suitable adjustment of the effective area of the orifices, together with the rate of liquid flow to the rotating nozzles and the pressure of the gases passing through the scrubber, the desired cleaning action may be obtained while using a minimum amount of

liquid. The invention accordingly provides a simple, efficient and commercially practicable scrubber which is capable of a wide variety of uses.

Although a specific embodiment of the invention has been set forth for purposes of illustration, it is to be understood that various changes and modifications may be made therein as will be readily apparent to a person skilled in the art. Certain specific terms have been used herein for convenience of description and not as a limitation to the scope of the invention. The invention is only to be limited in accordance with the following claims.

What is claimed is:

1. An apparatus for cleaning gases comprising a casing, a cleaning zone in said casing comprising a transverse plate having a plurality of openings therein forming orifices through which the gas passes at high velocity, baffle means disposed in registration with said orifices in a position such that the gases and entrained matter after passage through the said orifices impinge on said baffle means, means maintaining a liquid blanket on said transverse plate in which the entrained particles are trapped, means removing entrained droplets of said liquid from said gases comprising a plurality of drying units spaced transversely of said casing to receive gases after passage through said cleaning zone, each of said units comprising a set of vanes adapted to impart a rapid whirling motion to the gases passing therethrough, dividing means in said casing forming separate chambers communicating between the individual drying units and the cleaning zone, and means closing selected chambers for interrupting the flow of gases therethrough.

2. An apparatus for cleaning gases comprising a casing, means passing gases to be cleaned through said casing, a cleaning zone comprising a plate extending across said casing and having a plurality of openings therein forming fixed orifices through which the gas passes at high velocity and means comprising a plurality of louvers arranged over said plate and adapted to individually cover selected portions thereof for rendering the orifices of said portions ineffective while maintaining the remaining orifices unchanged, for thereby controlling the gas velocity without altering the characteristics of gas flow through said remaining orifices.

3. An apparatus for cleaning gases comprising a casing, a cleaning zone in said casing comprising a transverse plate having a plurality of openings therein forming orifices through which the gas passes at high velocity, means removing entrained droplets of said liquid from said gas comprising a plurality of drying units spaced transversely of said casing, each unit registering with a separate portion of said plate to receive gas after passage through the orifices therein, and a set of imperforate members, each adapted to block off the flow through the orifices in a predetermined portion of said plate for interrupting the flow of gas through said portion and through the aligned drying units, so as to control the gas velocity in the remaining area of said plate and through the remaining units.

4. An apparatus for cleaning gases comprising a casing, a cleaning zone in said casing comprising a transverse plate having a plurality of openings therein forming orifices through which the gas passes at high velocity, means removing entrained droplets of said liquid from said gas com-

75

- prising a plurality of drying units spaced transversely of said casing, each unit registering with a separate portion of said plate to receive gas after passage through the orifices therein, and
- 5 baffle means comprising a set of imperforate members interposed between said cleaning zone and said drying units to block off the flow through the orifices in a predetermined portion of said plate for interrupting the flow of gas through
- 10 said portion and through the aligned drying units, so as to control the gas velocity in the remaining area of said plate and through the remaining drying units.
- 15 5. An apparatus for cleaning gases, as set forth in claim 23, in which the imperforate members

comprise shields slidably mounted beneath said transverse plate for blocking off and closing the orifices in selected portions thereof.

6. An apparatus for cleaning gases, as set forth in claim 4, in which the baffle means comprises 5 louvers arranged over said plate and adapted to individually cover selected portions thereof.

7. An apparatus for cleaning gases, as set forth in claim 4, in which the baffle means comprises a set of dampers interposed between the cleaning 10 zone and the respective drying units for interrupting the gas flow to selected areas of said transverse plate and through selected drying units.
